UNITED STATES PATENT OFFICE.

ELLIS J. WOOLF, OF MINNEAPOLIS, MINNESOTA, ASSIGNOR TO THE WOOLF VALVE GEAR COMPANY, OF MINNEAPOLIS, MINNESOTA, A CORPORATION OF MINNESOTA.

REVERSIBLE EXPLOSIVE COMPOUND-ENGINE.

No. 878,925.

Specification of Letters Patent.

Patented Feb. 11, 1908.

Application filed April 5, 1907. Serial No. 366,480.

To all whom it may concern:

Be it known that I, ELLIS J. WOOLF, a citizen of the United States, residing at Minneapolis, in the county of Hennepin and State of Minnesota, have invented certain new and useful Improvements in Reversible Explosive Compound - Engines; and I do hereby declare the following to be a full, clear, and exact description of the invention, such as will enable others skilled in the art to which it appertains to make and use the same.

My invention relates to explosive compound engines.

The chief feature of improvement has for its object to provide such an engine with a simple and efficient means for controlling and reversing the same while in motion.

A minor feature of improvement enables the crank case to be utilized as a condensing and muffling chamber for the exhaust.

To the above noted ends, my invention consists of the novel devices and combinations of devices hereinafter described and pointed out in the claims.

The invention is illustrated in the accompanying drawings, wherein like notations refer to like parts through the several views.

Referring to the drawings; Figure 1 is a view in vertical longitudinal section through the entire engine in the plane of the crank shaft. Fig. 2 is a detail showing the controlling and reversing valve in the same plane as in Fig. 1, but in a different position, to-wit, the position it would take for reversing the engine. Fig. 3 is a similar view showing the said valve in the position it would take for stopping the engine. Fig. 4 is a detail in plan showing a portion of the high pressure cylinder joint flange illustrating the water injection port.

The numerals 1 represent a pair of base castings; the numeral 2 the high pressure cylinder casting, and 3 the low pressure cylinder casting. The casting 3 is provided with a removable head 3^a. The said castings 1, 2 and 3 are of such shape that, when rigidly secured together, they inclose and afford suitable bearings for the crank shaft 5, and that, when connected by pipe 4, they cooperate to form a common crank casing, which, in this design, serves as a muffling chamber 7, as will later more fully appear. The crank shaft 5 is provided with a suitable fly wheel 6.

In the high pressure cylinder casting 2 is

mounted a high pressure piston 8 of trunk form, the trunk portion of which opens to the crank case or muffling chamber 7. The said piston 8 is connected by a rod 9 to a crank 10 of the shaft 5. In the low pressure cylinder 3, is mounted a low pressure piston 11 which is also of trunk form, with the trunk portion thereof opening to the crank case or muffling chamber 7. The low pressure piston 11 is connected by a rod 12 with the crank 13 on the shaft 5.

The cylinder castings 2 and 3 are of the proper construction to afford joint flanges by which the said castings are rigidly connected together; and, in these joint flanges, are registering passages or openings which co-operate to afford the low pressure admission or connecting port 14 between the two cylinders. The low pressure cylinder casting 3 is also of the proper form to afford a seat for the combined controlling and reversing valve 15, and from the said seat also extend two ports marked, respectively, 16 and 17, which are controlled by said reversing valve and lead to opposite ends of the low pressure cylinder. The said low pressure cylinder casting 3 is also of the proper form to afford a chamber or chest 18, one wall of which forms part of the seat for the valve 15, and is provided with a charging port 19 therethrough controlled by said valve. The intake or explosive mixture supply valve 20 is shown as fitted to the lower end of a curved pipe 21 which, at its upper end, taps the charging valve casing 22^a in which is mounted the spring seated charging valve 22. The casing 22^a is screwed as a plug into the head of the high pressure cylinder 2. The pipe 21 is provided with a branch or T section 21^a which taps the chest 18. The valve 15 is provided with a port 15^a passing therethrough.

A part of the trunk portion of the high pressure piston 8 is cut away to afford an exhaust port 23 which co-operates, under the movement of the piston, with the connecting port 14, at the proper time, to afford the final exhaust and to deliver the same into the crank case or muffling chamber 7. This chamber 7 is tapped at 7^a by a suitable exhaust pipe, not shown. The explosion cylinder is shown as fitted with an ordinary jump spark plug 24.

The upper portion of the high pressure cylinder casting 2 is of the proper construction to afford a water jacket 25 surrounding 110

the explosion cylinder. The said casting 2 is also of the proper construction to afford a pump cylinder 26 in which is mounted a spring held pump plunger 27 provided with 5 suitable valve-equipped supply and delivery sections 28 and 29 for affording the forced circulation of the cooling water through the jacket 25. As shown, the spring held pump plunger 27 becomes subject to pressure from 10 the explosion cylinder, through the port 30, under the control of the high pressure piston. An overflow pipe 31 receives the water from the highest level in the water jacket 25, and is fitted with an air cylinder 32 above the 15 highest level of the water. The overflow pipe 31, at its lower end, taps through the joint flange of the high pressure cylinder casting, as shown best in Fig. 4, and delivers to a water port 33 shown as formed one-half 20 in each of the cylinder joint flanges; which water port 33 entirely surrounds the connecting port 14 between the two cylinders and opens directly thereto through the flange joint. The flange joint, outside the 25 water port 33, is packed, thus separating the flanges far enough to afford a passage for the water from the port 33 to the port 14. The high pressure piston 8 and its cross head 10 are lubricated through oil duct 34; the low 30 pressure piston and its cross head pin through oil duct 35, and the crank shafts and cranks through oil duct 36.

Operation. All the parts have now been specified. The general operation or action 35 of the engine will now be traced, but only so far as is necessary to render distinct the effect of the improvements herein disclosed and claimed. Otherwise than in respect to the improvements herein claimed, the engine 40 illustrated is of the same general design in point of principle or mode of operation as the engine disclosed and claimed in my pending application S. N. 360,148 filed March 2nd, 1907, but, in the present instance, the two 45 pistons are connected up to the common crank shaft with the high pressure piston 90 degrees in advance of the low pressure piston, instead of 105 degrees as shown in my said pending case. I connect the two pistons 50 tons 90 degrees apart, in the present instance, because the engine herein shown is designed to operate as a reversing engine.

In Fig. 1 of the drawings, the parts are 55 shown in the position that they would occupy just immediately after an explosion had taken place and the high pressure piston was about to begin its working stroke. It, of course, follows that the low pressure piston will be making its suction and exhaust 60 stroke. Tracing the gases, from the point of the intake valve 20, the explosive mixture, under the outward or suction stroke of the low pressure piston 11, will be drawn into the chest 18 through the pipe section 21^a and 65 thence through the charging port 19 and

the passage 15^a in the valve 15 and through the port 17 into the lower or crank shaft end of the low pressure cylinder. During this same time, the exhaust port 23 in the high pressure piston 8 will be in position for co-operation with the connecting port 14, and the port 16, to afford the final exhaust from the opposite or upper side of the low pressure piston 11; or otherwise stated, the spent gases will be forced out from the upper end 70 of the low pressure cylinder, through the connecting ports 16, 14 and 23 and into the crank case or muffling chamber 7 and out through the pipe opening 7^a, under the continued upward movement of the low pressure 75 piston 11. This suction and exhausting action of the low pressure piston 11 will continue, until the high pressure piston moves inward, under the effect of the explosion, far enough to close the connecting port 14; at 80 which time, the low pressure piston will have substantially completed its outward stroke and the lower portion of the low pressure cylinder will be filled with the explosive mixture which has been drawn therein 85 through the intake valve 20 and the charging port 19. As soon as the high pressure piston moves inward far enough, under the effect of the explosion, to uncover the connecting 90 port 14 and open the same to the explosion 95 cylinder, the partially expanded gases will be admitted from the high pressure cylinder, through the connected ports 14 and 16, to the outer or upper end of the low pressure cylinder; and this will occur just after the 100 low pressure piston has passed its upper center and is ready to begin its co-operative working stroke.

Under the inner or downward movement of the low pressure piston 11, the intake 105 valve 20 closes, and the mixture in the lower part of the low pressure cylinder will become subject to compression from said piston and thereby be forced through the port 17, the passage 15^a in the valve 15 and through the 110 charging port 19 into the chest 18 and out through the pipe section 21^a into the charging valve casing 22^a. This action continues until the high pressure piston has completed its working stroke and until the pressure 115 upon the engaged explosive mixture, from the low pressure piston 11, becomes greater than the pressure of the nearly spent gases in the two cylinders, on the working sides of the two pistons, whereupon the charging 120 valve 22 will open and admit the explosive mixture to the explosion cylinder, under the continued downward movement of the low pressure piston 11; and the two cylinders being still connected, at this time, through the ports 14 and 16, the spent gases, within the high pressure cylinder will be drawn over into the upper end of the low pressure cylinder, by the continued displacement produced therein under the continued down- 125 130

ward movement of the said low pressure piston. The inrushing charge of the explosive mixture, entering the explosion cylinder, assists the suction produced by the 5 downward movement of the low pressure piston to force the spent gases from the high into the outer end of the low pressure cylinder, thus making room for the fresh charge. As soon as the high pressure piston 0 8 moves outward far enough to cover the connecting port 14, the fresh charge will be caged in the explosion cylinder and be compressed therein; and, at the proper instant, be exploded, thus bringing all the parts back 5 into the position shown in Fig. 1, which was assumed as the starting position, for tracing the cycle of action.

Directing attention now to the structure for reversing the engine, it must be obvious 0 from the drawings and the foregoing description, that the valve 15 controls the charging ports and the low pressure admission ports, and that, by shifting the said valve 15 from the position shown in Fig. 1 5 to the position shown in Fig. 2, the deliveries through the said ports may be shifted to opposite sides of the low pressure piston. For example, with the valve 15 set in the position shown in Fig. 1, the low pressure admission 1 and final exhaust is through the ports 14 and 16 to and from the upper side of the low pressure piston 11, and the fresh supply of explosive mixture is through the ports 19, 15^a and 17 to and from the under side of said low pressure piston. If now the valve 15 be shifted to the position shown in Fig. 2, these deliveries will simply be reversed or shifted to opposite sides of the low pressure piston 11; or, otherwise stated, the low pressure admission and final exhaust will now be through the ports 14 and 17 to and from the under side of the low pressure piston; and the fresh charge will be through the ports 19, 15^a and 16 to and from the upper side of said low pressure piston 11. Whenever this shift of the valve 15 from one or the other of its two extreme positions is made; as, for example, from the position shown in Fig. 1 to the position shown in Fig. 2, with the engine under motion, the low pressure piston will be converted into a pump piston under the effect of the momentum of the moving parts running in their original direction, thereby causing the same to draw air in through the exhaust pipe and ports into the low pressure cylinder, on the then working or lower side of the low pressure piston, and to force the air therefrom into the high pressure cylinder where it will become engaged; and this action will continue and the pressure of the engaged air in the high pressure cylinder will become cumulative, until it becomes sufficient to overcome the momentum of the moving parts, whereupon the engine will automatically reverse, from the pressure

of said accumulated air, and be started thereby in the opposite direction. All the parts now being in position for the proper distribution of the gases under the new direction of the engine's motion, it will so continue to run. From the foregoing, it will be seen that the reverse occurs under an air cushioned action, and hence there is no violent shock or strain on any of the moving parts. Otherwise and briefly stated, this 70 gas engine will reverse with as much ease to the parts as a steam engine.

Having regard to the regulation or control of the engine, it must be obvious, from the drawings, that the valve 15 has its port 15^a 80 so disposed, in respect to the charging port 19, that the said port 15^a may be throttled more or less, by the proper movement of said valve, or be entirely cut off from communication with the charging port 19, as shown 85 in Fig. 3. It, of course, follows that the quantity of explosive mixture which is drawn in through the intake valve 20 and through the charging port 19, into the charging end of the low pressure cylinder and also 90 the charge which is forced therefrom back through the same passages to the charging pipe 21, can be varied, as desired, for controlling the speed of the engine. These 95 throttling or regulating movements of the valve 15 are all effected within such a narrow range or small arc of the valve's possible movement as not to throttle the low pressure admission port. This throttling action is equally available whether the said valve 100 15 be set in the position shown in Fig. 1 or in the position shown in Fig. 2; or, otherwise stated, the throttling action required for regulation, is available whether said reversing valve 15 be set to make the engine run in 105 one direction or the other.

When the valve 15 is in the position shown in Fig. 3, the supply of explosive mixture is cut off and both sides of both pistons are thrown into communication with each other, 110 thereby equalizing pressures in all directions; and the engine will only continue to run as far as it may under the momentum of its moving parts.

The water injecting devices herein disclosed are substantially the same as those disclosed and claimed in my identified pending application, wherein the advantages of taking water from the jacket of the explosion cylinder and injecting the same into the 115 partially expanded gases, on their passage through the cylinder connecting port from the high to the low pressure cylinder, were fully set forth. In the present case, however, the water pump (26-27) and the air 120 reservoir 32, and the water port 33, are so proportioned and located that the water will be injected therethrough into the connecting port 14, not only during the time that the said port 14 is open to the explosion cylinder, 125 130

but also during more or less of the time that the said port 14 coöperates with the final exhaust port 23 in the high pressure piston for effecting the final exhaust. It follows 5 that more or less of the water takes effect directly on the finally exhausting gases, after they leave the low pressure cylinder; and hence, as a result, this final exhaust will enter the crank case or muffling chamber 7 at a 10 comparatively low temperature. This presence of the said water makes it perfectly safe to utilize the crank case as a muffling chamber, as herein disclosed.

It is, of course, obvious that the introduction 15 of water, into the spent gases, when they are exhausting into the chamber 7, will condense the same. The cylinder connecting port 14 and the final exhaust port 23, in the piston 8, are both of greater area than the 20 discharge opening 7^a from the casing chamber 7; and, hence, it follows that, under the condensing action of the injected water on the spent gases, a partial vacuum will be produced and become effective on the low pressure 25 piston.

What I claim is:—

1. An explosive compound engine provided with a reversing valve controlling the low pressure admission ports, and which 30 valve is movable, at will, for shifting the admission to opposite sides of the low pressure piston, for reversing the engine, substantially as described.

2. An explosive compound engine provided with a reversing valve controlling both 35 the charging port and the low pressure admission port, and which valve is movable, at will, for shifting the deliveries through said ports to opposite sides of the low pressure 40 piston, for reversing the engine, substantially as described.

3. An explosive compound engine provided with a reversing valve controlling both the charging port and the low pressure admission port, and which valve is movable, at 45 will, for throttling the charging port and for shifting the deliveries through said ports to the opposite sides of the low pressure piston, for reversing the engine, substantially as de- 50 scribed.

4. An explosive compound engine having its high pressure piston connected to travel

in advance of the coöperating low pressure piston and controlling the low pressure admission port, and a reversing valve in said 55 port movable, at will, for shifting the delivery to opposite sides of the low pressure piston, for reversing the engine, substantially as described.

5. An explosive compound engine having 60 its high pressure piston connected to travel in advance of the coöperating low pressure piston and controlling the low pressure admission port, a charging port, and a reversing valve controlling the deliveries through 65 both of said ports and movable, at will, for shifting the said deliveries to opposite sides of the low pressure piston, for reversing the engine, substantially as described.

6. An explosive compound engine having 70 its high pressure piston connected to travel in advance of the coöperating low pressure piston and controlling the low pressure admission port, a charging port, and a valve 75 controlling the deliveries through both of said ports and movable, at will, for throttling the charging port and for shifting the said deliveries through both of said ports to opposite sides of the low pressure piston, for reversing the engine, substantially as de- 8 scribed.

7. A compound explosive engine having means for injecting water into the partially expanded gases on their passage from the high to the low pressure cylinder and also 8 into the spent gases when finally exhausting from the low pressure cylinder, substantially as described.

8. An explosive compound engine provided with an inclosed crank case receiving the final exhaust from the low pressure cylinder, and which engine is provided with means for injecting water into the spent gases as they are exhausting into said chamber, whereby said crank casing is utilized as a condensing and muffling chamber, substantially as described.

In testimony whereof I affix my signature in presence of two witnesses.
